REGENERATIVE SOAKING PIT FURNACE

John W. Carter and Andrew Reed Rowe, McKeesport, Pa., assignors to National Tube Company, a corporation of New Jersey

Application August 27, 1941, Serial No. 408,524

4 Claims. (Cl. 263—15)

This invention relates to regenerative soaking pit furnaces employed for heating steel ingots and the like.

In present furnaces of the character stated, considerable difficulty is encountered due to the escape of molten slag from the pit. This fugitive slag or liquor is formed upon the surface of the ingots and drips into the "bottom" of the pit. Although suitable drains are provided to remove this slag at certain intervals, the slag accumulates in the pit.

Such a condition is a continual hazard to the furnace structure, due to the affinity of the slag and the brick or refractory of the furnace which causes pitting of the latter, and upon repeated heating and cooling of the furnace structure in its regenerative operation, cracks are formed in the refractory through which the slag escapes in a downward and outward direction. Since the usual design of such furnaces locates the checker work entirely or at least partly below the level of the hearth and "bottom" of the pit, the fugitive slag eventually enters and clogs the checkers. In such a case, the furnace must be shut down and the checkers and refractory rebuilt, causing prolonged delays and considerable expense.

Such furnaces are a potential source of trouble and expense at all times because the time of failure is unpredictable, it being impossible to predetermine the life of the furnace brickwork even by change of refractory material, thickness, etc.

It is a prime object of this invention to so construct and arrange the furnace parts as to insure against the hazard of fugitive slag and to prevent the same from entering and clogging the regenerator chambers.

Our invention contemplates the construction and disposition of the regenerator chambers and checkerbrick at a sufficient level above that of the "bottom" of the soaking pit so that escaping slag cannot flow into said chambers but will escape therebeneath to regions where it will not injure the furnace.

Additional advantages in construction and operation of our improved furnace will become apparent from the following description taken in connection with the accompanying drawings, wherein:

Fig. 1 is a plan view of a regenerative soaking pit furnace embodying our invention;

Figs. 2, 3 and 4 are cross sectional views thereof taken on the lines II—II, III—III and IV—IV, respectively, of Fig. 1;

Fig. 5 is a view similar to Fig. 1 of a modified form of our invention; and

Figs. 6 and 7 are cross sectional views taken on the lines VI—VI and VII—VII, respectively, of Fig. 5.

Referring to Figs. 1 to 4 of the drawings, the improved soaking pit furnace illustrated therein includes side walls 2, end walls 3, a base 4 and a top 5 composed of suitable refractory material. At one end of the furnace is provided one or more soaking pits or chambers, generally designated 6, including a hearth 7 beneath the pit between said hearth and the top 5 of the furnace structure.

Immediately above the hearth 7, the top 5 is provided with one or more openings 9 through which ingots may be lowered to rest upon the hearth in upright position, as indicated at a. Covers or tops 10 are slidably mounted for covering said openings during heating. Air-cooled metal chill boxes 11 may be provided about the hearth 7 for cooling the latter, as is common practice.

In the opposite end of the furnace is provided a chamber or manifold 12 centrally connected with the stack 13 by a transverse passage 14 and with the atmosphere by a separate passage 15. A pair of reversing valves 16 are mounted for selectively connecting passages 14 and 15 with flue banks on opposite sides of the furnace, each flue bank consisting of a plurality of flues, three such flues being employed and designated 17, 18 and 19. Regulating valves 20 are provided in chamber 12 for each of said flues for balancing the flow of gases flowing through the flues.

Flues 17, 18 and 19 extend longitudinally along opposite sides of the furnace structure, being integrally formed therein of suitable refractory, and terminate in spaced combustion chambers 21 opening into the sides of the pit or chamber 6. Said chambers 21 extend vertically between arches 22 in the roof or top 5 of the furnace and bridge walls 23 extending along the sides of the pit at an elevation above the hearth 7 thereof.

Intermediate the run or longitudinal extent of each of the flues 17, 18 and 19, we provide checker chambers 24, each of said chambers being filled with checker brick as indicated in Figs. 2 and 4.

The furnace may be fired in the conventional manner, as by means of burners 25 inserted in the arches 22 of the furnace combustion chambers 21 of flues 17, 18 and 19 into the pit 6, said burners being supplied with gaseous fuel from any suitable source. The operation of the furnace upon the regenerative principle is controlled by the reversing valves 16 to supply air to one set of flues 17, 18 and 19 through the preheated checkers in chambers 24 thereof into the pit 6 while

drawing the products of combustion from the pit through the checker chambers 24 of the other bank of flues and out of the stack, and then reversing the flow. One such heating cycle is shown by the arrows on the drawings, the other cycle being an exact reversal of that so indicated, and being readily understood by those skilled in the art without further amplification.

Referring particularly to Fig. 2, it will be noted that we have disposed the flues 17, 18 and 19 and their checker chambers 24 completely and entirely above the level of the hearth 7 of the soaking pit 6, and above the level of the layer or "bottom" 26 of coke breeze or the like upon which the ingots *a* are placed. Said flues and checker chambers are also preferably above the tops of the bridge walls 23, so as to prevent overflowing molten slag from reaching the checker chambers.

By so elevating the flues and checker chambers, we provide a furnace construction which insures against damaged checkers and flues from fugitive or escaping molten slag, which may break through the hearth 7, as by failure of the refractory thereof by heat and by cracking of the chill boxes 11 while the furnace is in operation.

Attention is further directed to the disposition of the several checker chambers 24 in the same horizontal plane, thereby enabling a more uniform distribution of checkers and effecting considerable saving in the construction of the furnace over the more complicated structures previously employed. Further, the disposition of the flues 17, 18 and 19 and the checker chambers 24 in substantially the same horizontal plane, provides for a uniform flow of gases therethrough, permitting uniform distribution of the flow of the products of combustion and air through the series of flues and to and from the soaking pit 6 throughout the longitudinal length thereof.

Figs. 5 to 7 illustrate a modified form of furnace embodying our invention, wherein the plurality of flues on each side of the furnace is disposed in vertical alignment in the region of and alongside of the soaking pit, said flues having the portions thereof adjacent the stack end of the furnace disposed in horizontal alignment for communication with said manifold through the usual regulating valves. Since the parts of the modified furnace are similar to those previously described, except for the arrangement and location thereof, the same have been given like reference characters with the addition of the exponent *a* thereto.

As clearly shown in Fig. 6, the checker work 24^a is disposed in and along the respective flues 17^a, 18^a and 19^a, and the said checker work and flues are arranged in superimposed relation on each side of the furnace at a sufficient elevation so that the lowermost flues 17^a and their checker work are disposed above the hearth and "bottom" of the pit 6^a and above the bridge walls 23^a thereof. Hence, fugitive slag escaping through the refractory or brickwork of the "bottom" 26^a of the furnace or through the hearth 7^a will flow downwardly away from all of the flues and checker work without attacking or clogging the same.

As in the embodiment illustrated in Figs. 1 to 4, the modified construction illustrated in Figs. 5 to 7, employs a substantially horizontal passage and flow of gases with minimum interference to a uniform distribution thereof throughout the length of the soaking pit 6^a, and enables

the construction of a furnace of minimum overall width.

Thus, it will be seen that we have provided a regenerative soaking pit furnace embodying flues and checker work protected against attack and deterioration by slag escaping from the soaking pit, thereby eliminating one of the most destructive actions in furnaces of the character stated. A furnace constructed in accordance with our invention will have a greatly increased life, thereby enabling the continuous use thereof over longer periods of time, without shut-downs and repairs due to the ravages of molten slag.

It is to be further noted that the elevation of the flues and checker work above the level of the hearth and "bottom," together with the horizontal or vertical alignment of the flues and checker work of the banks thereof on opposite sides of the furnace, provides for a compact and economical furnace construction, with the improved efficiency and operation hereinbefore discussed.

Various changes and modifications are contemplated within the scope of the following claims.

We claim:

- 25 1. A regenerative furnace of the character described including a soaking pit, a hearth therein for receiving ingots thereon, combustion chambers on opposite sides of and communicating with said pit, means for firing the furnace located adjacent said chambers, means for reversing the flow of gases through the pit and combustion chambers, flues connecting said means and the combustion chambers and having checker chambers intermediate the extent of said flues, the flues and checker chambers being disposed at a sufficient elevation above the hearth to prevent a flow of fugitive slag from the latter into said flues and checker chambers.
- 30 2. A regenerative furnace of the character described including a soaking pit, a hearth therein for receiving ingots thereon, bridge walls on opposite sides of and elevated above the hearth, combustion chambers laterally beyond and above the bridge walls communicating with the pit, means for firing the furnace located adjacent said chambers, means for reversing the flow of gases through the pit and combustion chambers, flues connecting said means and the combustion chambers and having checker chambers intermediate the extent of said flues, the flues and checker chambers being disposed at a sufficient elevation above the bridge walls to prevent a flow of fugitive slag from the hearth into said flues and checker chambers.
- 35 40 3. A regenerative furnace of the character described including a soaking pit, a hearth therein for receiving ingots thereon, combustion chambers on opposite sides of and communicating with the pit, means for firing the furnace located adjacent the chambers, means for reversing the flow of gases through the pit and combustion chambers, plural series of flues disposed laterally on opposite sides of the furnace connecting the combustion chambers and said reversing means, said flues having checker chambers therein intermediate their lengths, said combustion chambers, flues and checker chambers being disposed in substantially the same horizontal plane entirely above the hearth level to prevent fugitive slag escaping from the latter from entering the said flues and chambers.
- 45 45 4. A regenerative furnace of the character described including a soaking pit, a hearth therein for receiving ingots thereon, combustion chambers on opposite sides of and communicating

with the pit, means for firing the furnace located adjacent the chambers, means for reversing the flow of gases through the pit and combustion chambers, plural series of flues disposed laterally on opposite sides of the furnace connecting the combustion chambers and said reversing means, said flues having checker chambers therein intermediate their lengths, the portions of

said flues and checker chambers adjacent the pit being superimposed in vertical planes on opposite sides of the furnace and disposed entirely above the hearth level to prevent fugitive slag 5 escaping from the latter from entering the said flues and chambers.
